BRACKET FOR LUMINAIRE MAST ARM

Alfred H. Stanley, Hinsdale, Ill., assignor to Joslyn Mfg.
and Supply Co., Chicago, Ill., a corporation of Illinois

Filed Feb. 12, 1962, Ser. No. 68,763

Term of patent 14 years

(Cl. D54—1)

FIG. 1 is a side elevational view showing a bracket for a luminaire mast arm showing my new design, the mast arm being shown in broken lines for illustrative purposes only;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a bracket for luminaire mast arm, substantially as shown and described.
